UNITED STATES PATENT OFFICE.

IRVING WM. PECK, OF MACON, GEORGIA.

CUSHION-COVER FOR FRUIT-CRATES.

1,282,711.

Specification of Letters Patent. Patented Oct. 22, 1918.

Application filed October 2, 1916. Serial No. 123,341.

To all whom it may concern:

Be it known that I, IRVING W. PECK, a citizen of the United States, and a resident of Macon, in the county of Bibb and State 5 of Georgia, have invented a certain new and useful Improvement in Cushion-Covers for Fruit-Crates, of which the following is a specification.

My invention is an improvement in 10 cushion covers for fruit crates, and has for its object to provide means in connection with the cover of the crate for permitting quick and easy attachment of a cushion to the said cover, the cushion being designed to 15 protect the contents of the crate from injury.

In the drawings:

Figure 1 is a perspective view looking from below of a crate cover with the cushion 20 in place;

Fig. 2 is a similar view before the placing of the cushion;

Fig. 3 is an enlarged partial longitudinal section through the cover and cushion;

25 Fig. 4 is a similar section showing one form of attaching means;

Fig. 5 is a view similar to Fig. 4, of a modified form of attaching means, and

30 Fig. 6 is a transverse section through the cover and the cushion.

In the present embodiment of the invention is shown a cover 1 which may be of any usual or desired form, being in the present instance a board of suitable size having 35 reinforcing strips 2 intermediate its ends and on one face, and is provided on the opposite face at its ends with transverse cleats 3 for engaging inside of the ends of the crate.

40 In practice it is not always desirable to attach the cushions at the factory where the crates are manufactured, but at another place, as for instance where the fruit is packed. It is desirable, however, that some 45 form of attaching means be provided in connection with the crate cover for permitting the easy attachment of the cushions without the necessity of disassembling the crate cover.

50 With this object in view, I provide strips 4 of paper of suitable width, and of a length corresponding approximately to that of the cleats, the said strips being inserted between the cleats and the cover, as shown more particularly in Figs. 2, 3, and 4, and with the outer edges thereof flush with the outer sides

of the cleats and the ends of the cover. The strips are of such width that a little more than half their width will extend inwardly beyond the cleat and lie upon the under surface of the cover, as shown in Fig. 2. This free portion of each strip provides an attaching means for the cushion shown in Fig. 3.

These cushions are formed by placing 65 upon a strip of paper the filling of the cushion, which may be excelsior or the like, and turning the edges of the strip over upon the cushion, as shown in Fig. 6. The cushion so formed is then cut into suitable lengths, 70 the lengths being such that they will fit loosely between the cleats on the cover, as shown in Fig. 3.

These cushions may be shipped in bales 75 and applied to the crates at the place of packing merely by inserting the ends of the cushion beneath the strips 4 and pasting the said strips to the ends of the cushion in the manner shown in Figs. 1 and 3.

With this arrangement, the strips 4 are 80 held firmly in place by the cleats, and the covers may be shipped to the place of packing without the cushions, so that any liability of damage to the cushions during shipping is eliminated.

In the embodiment of the invention shown in Fig. 5, the cover 6 has the reinforcing strips 7 and the cleats 8, and the strips indicated at 9 are secured to the under face of the cover at the inner sides of the cleats. A portion of the strip is left free extending along the inner edge of the cleat, as shown in Fig. 5, and outwardly beyond the lower face of the cleat, and this free edge of the strip provides a securing means for the cushion. 90 With this construction, the cushion is held on the cover between the cleats in the same manner as in Fig. 3, and the free edges of the strips 9 are turned over upon the ends of the cushion and pasted thereto in any suitable or desired manner.

In either arrangement, the strips are applied at the factory, in Figs. 1 and 2, before the cleats are placed, the strips being held in place by the cleats while in Fig. 5 the strips 105 may be applied at the factory or at any place, as for instance at the packing house where the cushions are placed.

I claim:—

1. A cover for crates having transverse 110 cleats adjacent to its opposite ends and attached to the under side thereof, and flex-

ible strips having edge portions held between the cleats, the free edges of the strips being adapted to be attached to the outer face of the cushion and placed upon the under side 5 of the cushion and secured to the cushion, to hold said cushion in place.

2. A cover for crates having transverse cleats adjacent to its opposite ends and at-

tached to the under side thereof, and flexible strips having edge portions held between the cleats, and a flat cushion placed against the under side of the cover and held in place by the said flexible strips, the free edge portions of the said strips being attached to the ends of the cushion.

IRVING WM. PECK.
